UNITED STATES PATENT OFFICE

HENRY ARMSTRONG, OF SYRACUSE, NEW YORK, ASSIGNOR TO THE O. M. EDWARDS COMPANY, INC., OF SYRACUSE, NEW YORK, A CORPORATION OF NEW YORK

DISPLAY MACHINE

Application filed October 31, 1928. Serial No. 316,192.

My present invention appertains in general to the art of display devices and specifically to machines for consecutive exhibition of a plurality of sheets or displays of advertising matter, display curtains, pictures, scenes and the like.

It has particular reference to that class of inventions embodying a plurality of display curtain supporting rolls which are successively traversed in pairs, behind a curtain roll unrolling and rolling up action concealing bar, across a display area, the display curtains being so disposed that one is being unrolled over the display area from off of one roll in transit while the display curtain previously exhibited is being rolled up on the associated roll in transit and removed from the display area, providing the illusion that one display curtain disappears into the other.

The object of my invention is to provide a machine of this character whereby the illusion or the display curtain roll unrolling and rolling up action concealing bars traverse the display area in one direction only and in which the display curtains are brought into view at one side of the display area, extend thereacross, and are subsequently obliterated in the same direction in which they appear to extend into view across the display area.

In describing this invention, reference is made to the accompanying drawings in which like characters designate corresponding parts in all the views.

Figure 1 is a front elevation, part being broken away, of the machine embodying my invention.

Figures 2 and 3 are respectively vertical sectional views on lines 2—2 and 3—3, Figure 1, looking in opposite directions.

Figure 4 is a horizontal sectional view taken on the line 4—4, Figure 1, certain components being omitted to clarify the view.

Figure 5 is an enlarged sectional view, parts being broken away, of the upper left hand side of the machine, taken substantially in the plane denoted by the line 5—5 in Figure 1, illustrating part of the frame structure and display curtain roll carriage track, together with actuating and escapement mechanism, and showing approximately one

actuator block in the position occupied approximately at the end of the rewinding movement of one of the display curtains, the position of the display curtain roll carriage being depicted in chain lines. 55

Figure 6 is a view similar to Figure 5 showing the position of one of the actuator blocks just prior to moving into interlocking or coupling engagement with one of the display curtain roll carriages preliminary to transit 60 of the latter across the display area.

Figure 7 is a view similar to Figure 5 showing the position of one of the actuator blocks while releasing one unit of escapement mechanism employed for holding the display curtain roll carriages at the entrance to the display area. 65

Figure 8 is a similar view showing the position of one of the actuator blocks just after it has interlocked with a display curtain roll 70 carriage and the latter is about to be advanced across the display area.

Figure 9 is an enlarged fragmentary transverse section of part of the frame structure, as it would appear when taken on the plane 75 designated by the lines 9—9 on Figures 1 and 8, illustrating the display curtain roll track and display curtain roll carriage actuating and escapement mechanism, the latter in the former figure being in different position to 80 that shown in the present view.

Figure 10 is a plan view, partly broken away, of one of the display curtain roll carriages.

Figure 11 is a front sectional elevation of 85 the construction shown in Figure 10, one of the display curtain rolls being shown in section.

Figure 12 is a cross section of the display curtain roll carriages, on line 12—12, Figure 90 11.

Figures 13 and 14 are diagrammatic views looking to the left and right respectively illustrating the unwinding and rewinding operations of the curtain rolls, the same being 95 shown in the positions occupied at the entrance and exit of the display area and the entrance and exit of the return path or rewinding area.

Figures 15, and 16 are diagrammatic views 100

similar to Figures 13 and 14 illustrating the position of the curtain rolls while traversing the display and rewinding areas.

Figures 17 and 18 are elevations taken at 5 a right angle to each other of one of the actuator blocks.

Figure 19 is a sectional view on line 19—19, Figure 17.

Throughout the following specification and 10 claims, the term "curtain" is intended to include any form of advertising display matter, pictures, scenes, and the like or equivalents which may be mounted on or connected indirectly to the supporting rolls therefor, 15 and the latter components with the object of brevity in view are designated by the term "rolls."

This machine comprises a plurality of 20 pairs of rolls movable in a closed cycle of movement in one direction across a display area, path or space, and in the opposite direction, across a return area, path, or space remote from the display area, path or space back to starting position; a curtain winding 25 on one roll of each pair of rolls and connected to the second roll of the next preceding pair of rolls, whereby when a pair of rolls moves across the display area, the curtain unwinds from the first roll and is spread 30 out over the display area, and after the pair of rolls has traversed the display area, the curtain is wound on the second roll of the preceding pair of rolls during movement of said preceding pair across the display area; 35 means whereby the curtain is rewound from the second roll of one pair of rolls onto the first roll of the preceding pair of rolls during movement of the pairs of rolls across the return area, path or space, mechanism for intermittently actuating the pairs of rolls or 40 the carriages therefor, and stopping two of the pairs of rolls at the entrances and exits of the display and return areas while intermediate pairs of rolls are moving across said 45 areas, and means for timing or controlling the winding actions of the rolls.

In the illustrated embodiment of my invention, the pairs of rolls are shown as movable in an oblong cycle of movement, the front 50 and rear sides of the oblong being respectively the curtain display and return or rewinding areas.

To facilitate comprehension of the structure and purpose of the units and components 55 of the invention, I will first refer to the cycle of movement of the pairs of rolls and the curtains carried thereby, and subsequently to the invention in detail.

The numerals 1 and 2 designate, broadly, 60 the first and second, or the high and low tensioned rolls of each pair of rolls, and 3 the curtains connected at the ends thereof to the opposed rolls of the several pairs of rolls. Thus all of said pairs of rolls are interconnected by said curtains in a closed series.

The display area heretofore referred to and designated at A comprises that portion of the front of the machine bounded at the top and bottom of the machine by the lines a—b and c—d, the same extending transversely from lines e—f to g—h. The structure shown is usually supported in a case having a glass covered front, the sides of which terminates substantially at the lines denoted. The aforesaid carriages carrying said rolls 1 and 2 supporting the curtains 3 traverse said display area in intermittent timed relation and successively exhibit the display matter on the curtains, in the following manner:

In Figure 13 a pair of rolls is shown at the entrance to the display area A, being designated at a. A curtain 3 connected to the second roll 2 of said pair of rolls a is stretched across said display area and is connected at its lower end to roll 1 of a pair of rolls b at the exit end of the display area A. In Figure 15, this pair of rolls a is shown being advanced across the display area A, the curtain 3 shown stretched across said display area in Figure 13 being wound up on roll 2 of the pair of rolls a, while another curtain 3 is being unrolled from off of roll 1 of the pair of rolls a, the upper end thereof being connected to roll 2 of the pair of rolls c. Thus the upper and lower ends of the two curtains extending into the display area A are stationary and the upper curtain is being unrolled across the display area A while the preceding curtain is being rolled up and removed from said display area. Both of said curtains lie in the same plane and by means of an illusion bar, presently referred to, carried immediately forward of each pair of rolls, curtain roll unrolling and rolling up action is concealed from view and the illusion that one curtain disappears into the other is produced.

The pairs of rolls are actuated intermittently and successively in one direction across the display area A and in the opposite direction across the return or rewinding area B, and timed escapement mechanism controlled by roll carriage actuating mechanism, stops the pairs of rolls following and preceding the pairs of rolls moving across said display and rewinding areas at the entrances and exits of said areas. During this successive intermittent movement, the pairs of rolls come successively to the return or rewinding area B from the display area A and the curtains are wound on rolls 2 of the several pairs of rolls, and as one pair of rolls is progressing across the rewinding area B, roll 1 of that pair is held from movement so that the curtain connecting it and the roll 2 of the next following pair of rolls held at the entrance of the rewinding area B is unwound from the roll 2 of the pair held at the entrance of said rewinding area, and when the pair which is traversing said rewinding area reaches the end thereof, roll 1 is released from its holding

mechanism and is wound up by the winding means therefor to again wind the curtain 3 thereon as the following pair of rolls is progressing across said rewinding area, so that the curtain is again wound up on roll 1 ready to be again unrolled therefrom and displayed when moved around to the entrance of the display area. Hence, the pairs of rolls move in a closed cycle, and are moved intermittently 10 and successively across the curtain display and rewinding areas.

Rolls 1 and 2 consist of a barrel or tube 4 having collars 5 secured in the ends thereof, which are bored out to retain annular type ball bearings 6 through which the spindles 7 extend. The bearings 6 are held in the collars 5 by collars 8 secured to said spindles. Coil springs 9 are mounted on said spindles and are connected thereto at one end as at 10 15 and to collars 5 as at 11 at the other ends. These coil springs serve to rotate the barrels 4 of said rolls and wind or roll up the curtains 3 thereupon.

The spring 9 of the roll 1 of each pair of 25 rolls may be made of heavier gauge wire than spring 9 in each roll 2, so that when said rolls are wound up, each being rotated a corresponding number of revolutions, the rolls 1 will exert approximately fifty percent (50%) 30 greater winding torque than rolls 2. Under certain adaptations, such variation in roll winding torque may also be effected by giving rolls 1 several more revolutions than rolls 2 when the rolls are wound up manually preparatory to operation of the machine. Rolls 35 of high and low winding tension are required to effect proper timing actions for winding and unwinding of the curtains as hereinafter disclosed.

Rolls 1 and 2 are supported by carriages comprising cast brackets 12 and 13 arranged at the ends thereof and secured to sheet metal channel shaped frame members 14 and 15 which are united in the form of an I beam and carry an illusion or curtain roll winding and unwinding action concealing bar 16 on the forward side thereof, that is to say the forward side when the roll carriages traverse the display area A. The spindles 9 are reduced 45 at one end as at 17 and seat in apertures in the ends of said brackets. A collar 18 is secured to each spindle 9 in close proximity to the reduced end thereof by the rivet pin 19 and an arm 20 is fastened to each said collar. Each 50 arm 19 carries a pin 21 at the side of the spindle 7 and said pins seat in end brackets 12-13. These pins serve to prevent the spindles 7 from turning. The spindles 7 at the opposite ends thereof may be secured between 55 lugs 22 integral with brackets 12-13.

A ratchet 23 is mounted at the end of each roll 1 and 2 and these ratchets are engaged by pawls 24 pivoted at 25 to the arms 19. Coil springs 26 supported by said arms and 60 engaging said pawls serve to tension the latter

into engagement with the said ratchets. Rollers 27, conveniently in the form of annular type of ball bearings are mounted on pins projecting laterally from said pawls. These rollers coact with tracks on the frame structure of the machine hereinafter described and serve to intermittently release said pawls from said ratchets. Attention is invited to the fact that the teeth of the ratchets 23 on rolls 1 are milled in the opposite direction to the teeth on ratchets 23 on rolls 2; also that the pawls are disposed in opposite directions to coact with said ratchets. A cam 29 is mounted on the end of each roll 2 at the end thereof opposite ratchet 23. These cams serve to "set" the rolls 2 for proper exhibition of the curtains 3.

Each bracket 12-13 is provided with a centrally located pin or trunnion generally indicated at 30, by means of which the roll carriages are engaged and traversed across the machine. Each trunnion may comprise a pin 31 mounted in brackets 12-13 upon which a roller 32 is free to rotate, being held in position by a washer 33. The trunnions 30 are 90 disposed centrally intermediate pairs of rollers 34, conveniently annular type ball bearings mounted on pins 35 extending from said brackets 12-13. The trunnions 30 and rollers 34 are arranged in axial alignment with rollers 1 and 2 and said trunnions and rollers on each pair of brackets 12-13 at the ends of each carriage are directly opposed in vertical alignment. Rollers, also annular type ball bearings indicated at 36, are mounted on brackets 12-13 substantially centrally thereof. The axes of these rollers are at right angles to the plane in which the axes of rollers 35 lie. These rollers bear against the track sections on the machine frame structure later described, and serve to prevent excessive longitudinal shifting of the roll carriages.

The roll carriages described are nested about the ends of the machine frame structure in retaining magazines and are held in proper working spaced relations by means of the arcuate ends 37 on brackets 12-13 which contact when the roll carriages are nested. Note that these arcuate bracket ends 37 project a short distance beyond the peripheries of rollers 34 to permit free rotation of the latter when the roll carriages are nested as shown in Figures 2 and 3.

The rolls and carriages described are supported in parallel relation on a frame structure comprising two track sections generally indicated at 38 and 39. Each track section comprises a track run in which the carriage rollers 34 travel in transit and include front and rear runs 40 and 41 connected at their ends by substantially semi-circular end runs 42 and 43 which constitute roll carriage magazines. The track end runs referred to are conveniently in the form of castings 44-45 having opposed machined surfaces 46-47 be-

tween which rollers 34 run and against which they bear. The front and rear track runs include pairs of parallel spaced upright bars 48-49 connected to or contiguous with the track end run castings 44-45, so that the spaces between the bars of each pair of bars and the surfaces 46-47 of the track end run castings form endless track runs for the roll carriage rollers 34. Attention is directed to the fact that the faces 50 of the track end run castings are finished and are flush with the sides 51 of bars 47. Thus the inner ends of the track sections 38-39 provide tracks against which rollers 36 bear to prevent excessive longitudinal shifting of the roll carriages.

Tie rods 52 extend between and are secured to the track end run castings 44-45 by adjusting nuts 53. These tie rods serve to retain the two track sections 38-39 in proper spaced relation and the adjusting nuts thereon provide convenient means for adjusting the relation of these units in setting up the machine, and the carriage actuating conveyors in particular, which are later described.

Referring now to Figure 4, bearing retainers 54 are mounted on the outer sides of the plates 55 bridging the upright bars 48-49 and these retainers support annular type ball bearings not shown through which the line shaft 56 extends. Sprockets 57 and 58 are keyed on this shaft near the ends thereof, in vertical alinement with sprockets 59-60 keyed on idler jack shafts 61-62, the latter being journalled in annular type ball bearings mounted in retainers 63 supported by bridge plates 64.

In Figures 2 and 3, it will be seen that the pitch diameters of the sprockets are tangent to lines intersecting the centers of the spaces intermediate the upright bars 48-49, and that the axes of these sprockets lie intermediate end run castings 44-45. In Figure 9, one sprocket 59 is shown in section. An annular shoulder 65 having side faces 66-67 is formed on each sprocket. Laterally projecting annular flanges 68, 69 extend from the shoulder 65. These sprocket shoulder and flange surfaces provide guiding means for the two U-shaped actuator blocks 70, 71 mounted in equi-distant spaced relation on each conveyor chain 72 and 73. Said blocks are clearly shown in Figures 17, 18, and 19.

Each actuator block has side walls 74, 75 terminating in flat surfaces 76 at right angles to the faces of the side walls 74, 75. These side walls straddle the shoulder 65 of said sprockets and the surfaces 76 of the former contact with and bear against the flanges 68, 69 of the latter, which surfaces, shoulders and flanges serve to guide the actuator blocks 70, 71 over said sprockets and prevent excessive side wobble or tilting thereof, to enable entrance of said actuator blocks into

guiding means therefor intermediate said sprockets; and presently described.

The actuator blocks 70, 71 are connected to the conveyor chains 72, 73 by means of pins 77, 78 spaced from the center pin 79, 70 distances equal to the center distances of a chain link. The outside diameters of pins 79 correspond with the outside diameters of chain link rollers, and these pins serve as equivalents to chain link rollers for engagement with the teeth of said sprockets. Each pin 79 is provided with two shoulders or collars 81 which are free to rotate in the side walls 75, 76 of each actuator block 70, 71. An arm 82 is connected to rotate each pin 79 by means of a key pin 84. A shoulder in the form of two rollers 84, 85 is mounted on the end of each pin 79 and a single roller 86 is mounted on the opposite end of each said pin. Another shoulder in the form of two rollers 87, 88 is mounted on the free end of each arm 82 in alinement with rollers 84, 85. A single roller 87 is mounted above roller 86, and two rollers 90, 91 are mounted with axes at right angles to rollers 84, 85, 90, 86 and 89. Thus the actuator blocks are provided with hinged arms carrying what may be broadly termed as spaced apart shoulders which in effect form a recess for receiving a roll carriage trunnion or pin 30 at each end of each roll carriage, one of said shoulders of each actuator block being shiftable to permit the trunnions 30 to be received to interlock therebetween and to pass out or escape from between said shoulders. The arms 82 are normally tensioned laterally with respect to the actuator blocks 70, 71 as best shown in Figure 18, each by means of a coil spring 92 engaging extension 93 on each arm 82 and retained by pin 94 on each of said actuator blocks.

The rollers referred to serve to guide said actuator blocks when in transit with said conveyor chains, actuate escapement mechanism and engage and discharge roll carriages. Since these actuator blocks in performing these functions due to stresses set up tend to tilt out of alinement with respect to, the conveyor chains 72, 73 and the sprockets referred to, it is necessary to maintain alinement of the same with respect to roll carriage escapement mechanism and said sprockets over which they ride in reversing the direction of travel thereof. For this purpose, vertical tracks are provided in the form of vertical bars arranged in parallel relation with respect to track bars 48, 49. A pair of bars 95, 96 are arranged in parallel spaced relation with and laterally of bars 48 to provide a track between and receive rollers 90, 91, bars 96 being in spaced relation with respect to bars 48. A pair of bars 97, 98 are arranged in parallel spaced relation to and laterally of bars 49, bars 98 being spaced with respect to bars 49. The opposed surfaces 95' and 96' 130

of bars 95, 96 and 97' and 98' of bars 97, 98 provide tracks for rollers 84, 87, 88 and 89. In such instances where the bars 95 extend above and below the sprockets 57, 58, 59 and 60, as herein shown, it is necessary to recess the upper ends of said bars adjacent the rear track runs and the lower ends of said bars adjacent the front track runs, in a path at equal radial distances from the axes of said 10 sprockets, as denoted in Figure 5 by the arc *e-f*, so that the rollers 89 on the actuator blocks 70, 71 will not be obstructed when the latter ride over said sprockets. These several bars are held in spaced relation by suitable 15 means such as spacer pins 99 which extend therebetween, the reduced ends 100 of which extend through and are riveted to said bars. The upper and lower ends of bars 48, 49 are bolted to the end run castings 44, 45 as at 101, 20 which together with the bridge plates heretofore referred to, and the bridge plates 102, provide a very rigid track frame structure.

The upper and lower ends of the bars 97 of each said track section are arcuately formed 25 at equal radial distances from the axes of the sprockets 57, 58, 59 and 60, to permit the rollers 86, 87 on actuator blocks 70, 71 to ride over same, when running over said sprockets. The ends of bars 98 of each track section 30 terminate in close proximity to and intermediate the axial centers of the aforesaid sprockets, denoted by lines A—B and C—D. The upper ends of the bars 98 arranged laterally of the track front runs 40 terminate in the form 35 of cams 103, and the ends of the bars 98 arranged laterally of the rear track runs 41 are likewise formed. These cams constitute part of the roll carriage escapement mechanism.

40 At the entrance to the curtain display and rewinding areas A and B, the roller carriages are retained by escapement mechanism arranged on each track section in transverse alinement. The same may be in the form 45 of detents 104 pivoted on pins 105 and articulated by pins 106 to motion transmitting levers 107 pivoted at 108, the latter being provided with cam surfaces 107' which project into the said front and rear track runs into 50 the paths of travel of the actuator block rollers 84. The free ends 109 of detents 104 extend into said front and rear track runs into the paths of carriage trunnions 30 and clear of the actuator block rollers 85, 86, being tensioned by means of coil springs 110 55 engaging extensions 111 thereon and by pins 112. Inward movement of the detents 104 is determined by pins 113 carried thereby which bear against stop pins 114 on the said 60 track sections.

The free ends of the detents 104 extend to a point where they form abutments or stops for the roll carriage trunnions 30 when the latter lie in transverse axial alinement with 65 axes of sprockets 57, 58, 59 and 60. This

arrangement permits very accurate functioning of the actuator block arms 82. The actions of the latter are best shown in Figures 5, 6, 7 and 8. In Figure 5, one actuator block 70 is shown at the exit end of the curtain 70 rewinding area B, having discharged a curtain roll carriage into the magazine space thereabove. In this figure, the arm 82 is shown disposed at an obtuse angle with respect to the actuator block, being tensioned 75 to this position by spring 92. It is also apparent that the peripheries of rollers 87, 88 on said actuator block arm are tangent with the arc *a-b*, and that the periphery of the roll carriage trunnion 30 is also tangent with 80 this arc. The object of this is to permit said rollers to pass the said trunnions and enter intermediate the same and the cams 103. Note also in this figure, that the roller 84 is in contact with cam surface 107' on the motion 85 transmitting lever 107 and that the detent 104 has not yet shifted. From this figure, it will be seen that the roller 88 is projecting under the carriage trunnion 30 and that this roller 90 is in contact with cam 103.

As the actuator block 70 advances around said sprocket, as shown in Figure 7, the cam 95 103 forces the roller 88 under the trunnion 30 so that the latter lies between rollers 84 and 88. The roller 84 bearing against cam surfaces 107' on lever 107 forces the latter outwardly, carrying the detent 104 out of the path of travel of trunnion 30, permitting the roll carriage to be advanced as shown in Figure 8 across the adjoining track run. As the 100 carriage trunnion moves away from the detent 104, the latter under tension of spring 110 swings back into the track run and into the path of the succeeding roll carriage trunnions to arrest movement of the latter.

105 A detent 115 is pivoted at 116 on each track section 38, 39 at the exit ends of the front and rear track runs 40, 41 providing pairs of detents in transverse arrangement. The free ends 117 of said detents extend into said track 110 runs providing abutments or stops for the roll carriage trunnions 30 after the roll carriages are traversed across the curtain display and rewinding areas A and B and are 115 discharged from the actuator blocks. Referring again to Figure 8, attention is invited to the fact that the trunnions 30 of the roll carriages are held between the rollers 85, 88 on the actuator blocks 70, 71 and are discharged from therebetween as said actuator 120 blocks advance around the sprockets 57, 58, 59 and 60. This is clearly disclosed in Figure 5. The roller 85 is mounted on each said actuator block and forces the trunnion engaged thereby clear of the path of travel 125 of the periphery of said roller, as denoted by arc *c-d*, Figure 5. The relation of the detents 115 with respect to the axes of sprockets 57, 58, 59 and 60 is such that the said rollers 85 carry the carriage trunnions 30 a short dis- 130

tance beyond the point where the latter are released from the said rollers, as indicated in dotted line position at 30^a in Figure 5, this overriding of the carriage trunnions permitting the detents to swing back under the carriage trunnions 30 before the latter are released. These detents are forced back to the position shown by means of coil springs 118 engaging extensions 119 on said detents and retained by pins 120 on said track sections. Movement of said detents is limited by means of pins 121 carried thereby and abutting pins 122 on said track sections.

In Figure 1, it will be noted that the actuator blocks 70 and 71 are spaced equally apart on the conveyor chains 72, 73 and that the former are arranged in transverse alinement, so that the escapement means arranged on each said track section is operated simultaneously, thereby keeping the roll carriages in transverse alinement and parallel relation permitting uniform stretching of the curtains 3 across the display area A.

The lines A—B and C—D before referred to extend axially through the entrances to the curtain display and rewinding areas A and B. Lines E—F and G—H, Figures 13, 14, 15 and 16 extend axially through the trunnions 30 on the roll carriages at the points where the latter are retained by detents 115 at the exits of the curtain display and rewinding areas A and B. Hence it is obvious that the spaces intermediate lines A—B, G—H and C—D, E—F constitute respectively the curtain display and rewinding areas A and B, and the spaces above and below said end track runs E—F, A—B and G—H, C—D form the end magazines in which the roll carriages are accumulated or nested.

The roll carriages by means of the actuating means and escapement mechanism described are successively conveyed across the curtain rewinding and display areas A and B. More specifically, a pair of rolls is engaged and released from the upper magazine space referred to at the entrance to display area A and simultaneously a pair of rolls is engaged and released from the lower magazine space referred to. These pairs of rolls are simultaneously traversed across the display and rewinding areas A and B, and are simultaneously discharged into said magazine spaces at the exit ends of the display and rewinding areas A and B. The actuator blocks which engage and convey the roll carriages, ride over the sprockets 57, 58, 59 and 60 intermediate the end magazines, by means of which roll carriages are simultaneously discharged into the magazine space referred to and other roll carriages are engaged and released from the other ends of said magazine spaces and are traversed across the curtain display and rewinding areas A and B. By means of this form of construc-

tion, the display curtains are displayed one after the other across the display area A in intermittent timed relation, the period of intermittency being the time required for said actuator blocks to travel over the said sprockets from roll-carriage discharge to roll carriage display position, as hereinafter described.

The curtains 3 are timed in transit so that they are rolled up on rolls 1 at the entrance to the curtain display area A, and roll from off of said rolls as each said pair of rolls traverses the display area A, and the curtains displayed are subsequently rolled up on rolls 2 of each succeeding pair of rolls. This timing action is brought about by means of the ratchets 23 on the rolls 1 and 2 and the pawls 24 which mesh with and control rotation of said ratchets. These pawls are released from said ratchets by means of track 123 on track section 38 and track 124 on track section 39. These tracks are in the form of projections extending laterally inwardly from said track sections and in line with the paths of travel of the pawl rollers 27, best shown in Figure 9. Track 123 extends from a point 123^a a short distance under line E—F, around the end run casting 44 and downwardly a short distance beyond line C—D terminating at 123^b. Track 124 extends from a point 124^a a short distance above line C—D, around end run casting 45 and upwardly beyond line A—B terminating at 124^b.

The actions of the ratchet pawls 24 are as follows: Rolls 1 and 2 are rotated manually when the machine is set up to wind up the springs therein so that the latter in operation tend to turn the rolls in the directions indicated by the arrows α in Figures 13 and 14. In these figures, both rolls 1 and 2 of the pair of rolls α are shown free to rotate under spring winding tension, the pawls 24 being released from ratchets 23, this being effected by pawl rollers 27 bearing against said tracks 123, 124. Roll 1 of the pair of rolls α at the exit end of the display area A is locked against rotation, since the pawl roller 27 has run off of the end 123^b of track 123 and the pawl 24 is in engagement with ratchet 23. Roll 2 of this pair of rolls is shown free to rotate in Figure 14 since the pawl adjoining said roll is released from ratchet 23 thereon, the roller 27 on said pawl bearing against track 124. Note that the cam 29 on roll 2 on the succeeding pair of rolls α is directed downwardly. This is brought about due to the location of the fastening points or lines of the curtains 3 with respect to said rolls 2. Under winding torque of rolls, which are high tensioned, the curtains are wound up tight on said rolls when moved to the position occupied by the pair of rolls α , and the curtains pull in axial alinement with said rolls. As the pair of rolls α is released from the position occupied at the entrance to the display area A and is

traversed thereacross, as shown in Figure 15, the succeeding pair of rolls *e* lowers to the position previously occupied by the pair of rolls *a*, and the cam 29 on roll 2 contacts with roll 125 supported by bracket arm 126, which is mounted just below the plane denoted by the line A—B on track section 38. This roll 125 serves to tilt cams 29 upwardly, thereby bringing the curtains 3 tangent with the surfaces of rolls 2, this being necessary to bring the curtains 3 into vertical alinement so that they appear to travel in the same vertical plane. These cams also serve to prevent the rolls 2 from turning so that the curtains 3 are unrolled from off of rolls 1 and are stretched across the display area A. Roll 2 of the pair of rolls *a*, being free to rotate, winds up the curtain connected thereto and removes the same from the display area A, roll 1 to which the other end of the curtain is attached being held from rotation by pawl 24 engaging ratchet 23 thereon.

Pawl 24 are released from ratchets 23 permitting rotation of rolls 2 when the latter are traversed around through the lower magazine space. Note in Figures 14 and 16 that the pawl 24 is released from the ratchet 23 on roll 2 of the pair of rolls *d* at the entrance to the curtain rewinding area B, and that the pawl 24 is released from ratchet 23 on roll 1 of the preceding pair of rolls, indicated at *e*, and located at the exit end of the rewinding area B. As the pair of rolls *d*, advanced across the curtain rewinding area *b*, (see Figures 15, 16), pawl 24 engaging ratchet 23 on roll 1 prevents the latter roll from winding up, so that the curtain 3 is unrolled from off of roll 1 of the following pair of rolls *f*. At the exit of the rewinding area, the high tensioned roll 1 of the pair of rolls *e* rolls up the curtain 3 thereupon so that the curtains are rolled up on the roll 1 or high tensioned rolls of the pairs of rolls advancing to the entrance of the curtain display area A. The high tensioned roll 1 of each pair of rolls is free to rotate when travelling through the upper magazine space. In this manner, the timing actions of the curtains 3 are controlled in unison with the actuation of the roll carriages throughout the closed cycle of movement.

Prior to operation of the machine, the rolls 1 and 2 are wound up manually a sufficient number of revolutions to stretch the curtains 3 taut across the display area A, and also so that rolls 1 are so tensioned that they exert approximately 50% greater winding torque than rolls 2. The said rolls are wound up so that they normally tend to turn or rotate in opposite directions or in other words, rolls 1 tend to turn counter clockwise and rolls 2 clockwise, the teeth on the ratchets 23 on the respective rolls 1 and 2 being formed in opposite directions so that when engaged with pawls 24 they are restrained from rotation

by the coil springs 9 thereof. The pawls 24 and ratchets 23 serve to lock the rolls from unwinding when the rolls are removed from the machine by an operator to change the curtains 3.

In the operation of the machine, line shaft 56 is driven at a uniform speed of rotation by any suitable prime mover such as an electric motor geared through the medium of a speed reducing unit and chain drive over sprocket 127 on the end of said line shaft. Since sprockets 57 and 58 are keyed to the shaft 56, the conveyor chains 72, 73 are driven at a uniform speed, and the actuator blocks 70, 71 on each said conveyor chain are in constant motion through a closed cycle of travel. By means of the two actuator blocks 70, 71 arranged in equidistant spaced relation on said conveyor chains, roll carriage coupling and discharging actions at the extremities of the machine are simultaneous and one roll carriage is being traversed downwardly across the display area A, while another roll carriage is being conveyed upwardly across the rewinding area B. Thus it will be seen that the cycles of actions are constant and that the driving forces of the conveyor chain 72, 73 are substantially balanced, providing a very uniform operating machine.

Assuming that a pair of rolls 1, 2 is about to enter the display area A and another pair of rolls 1, 2 is about to enter the rewinding area B, the relation of the several pairs of rolls will be substantially as shown in Figure 13, the pairs of rolls referred to being indicated at *a* and *b*. The actuator blocks 70, 71 on conveyor chain 72, 73 may occupy the position shown in Figure 5 on each sprocket 57, 58, 59, 60, that is to say the actuator blocks have just completed a roll carriage discharging operation. These actuator blocks then ride over the said sprockets and approach the pairs of rolls *a* and *d* and the rollers 84 on said actuator blocks coact with cam services 107 on motion transmitting levers 107 following coupling action of the rollers 85, 88 on the actuator block arms 82 with the roll carriage trunnions 30. The motion transmitting levers are then pressed outwardly, swinging the detents 104 out of the paths of travel of the roll carriage trunnions 30, and the latter, now securely coupled to the actuator blocks, are conveyed by said actuator blocks into the curtain display and rewinding areas A and B.

As the pair of rolls *a* lowers from the position occupied in Figure 13 into the display area A, the succeeding pair of rolls *c* through force of gravity and bearing against the pair of rolls *a* lowers also in unison with the travel of the latter and abut the detents 104, by which said pair of rolls is restrained in position at the entrance to the display area. During the lowering movement of said pair of rolls *c*, cam 29 on roller 2 coacts with roller

125

130

125 and the latter forces said cam to tilt upwardly so that the curtain 3 connected to the roll 1 of the preceding pair of rolls *a* will pull tangentially from roll 2 of the pair of rolls *c*. This roll setting action is brought into view in the curtain displayed area A. Also, before the pairs of rolls reach the positions occupied by the pair of rolls indicated at *c*, in Figure 13, and before the cams 29 on rolls 2 are tilted back as referred to, said rolls are released by pawl rollers 27 on pawls 24 engaging ratchets 23 on rollers 27 riding up on the end 124^b of track 124 to permit rotation of said rolls at this point and subsequently across the display area A.

At the same time, the pair of rolls *d* moves upwardly and due to the winding tension of rolls 2 of the following pair of rolls *f*, the latter pair of rolls is pulled upwardly until the same are arrested by the pair of detents 104. Immediately after pair of rolls *d* starts to move upwardly across the rewinding area B, pawl roller 27 runs off the end 124^a of track 124 and a pawl 24 engages ratchet 23 on roll 2 of said pair of rolls, thus preventing said roll from winding up, due to the rather remote possibility of foreign matter entering the bearings of and hampering the rotating action of roll 1 of the preceding pair of rolls *e*.

During movement of the pairs of rolls *a* and *b* across the curtain display and rewinding areas A and B, curtain 3 is unrolled from off of roll 1 of the pair of rolls *a* traversing the display area A, and this roll, exerting greater pulling force on the curtain stretched therebetween and roll 2 of the pair of rolls *c* than the said roll 2, pulls said curtain taut and holds the cam 29 on said roll 2 against the roller 125. The preceding curtain stretched between roll 2 of the pair of rolls *a* and roll 1 on the preceding pair of rolls *b* is being wound up on said low tensioned roll 2 because the high tensioned roll 1 of the pair of rolls *b* is restrained from turning by the pawl 24 engaging ratchet 23 on said latter roll. At the same time, roll 1 of the pair of rolls 3 is winding up the curtain stretched between the same and roll 2 of the pair of rolls *d*, pulling the curtain in line with the axis of the last mentioned roll, due to the variation in winding torque between the rolls 1 and 2. Roll 1 of the pair of rolls *d* in transit being held from rotation, unrolls the curtain interconnecting the same and roll 2 of the following pair of rolls *f* stationary at the entrance to the rewinding area B from off of the latter roll. Just prior to discharge of the pairs of rolls which have traversed the display and rewinding areas A and B into the end magazines to be retained at the exit ends of the front and rear track runs by the two pairs of detents 115, roller 27 on pawl 24 engaging roll 1 of the pair of rolls at the exit end of the display area A runs from off of the end 123^b of

track 123 so that just as soon as said pair of rolls stops, roll 1 will be locked by said pawl and ratchet and the winding force of said roll will be arrested, so that roll 2 of the following pair of rolls will pull and hold the curtain 3 stretched across the display area A taut and will wind the same up as that succeeding pair of rolls is traversed across the display area, the cam 29 on said roll 2 turning away from roller 125 in clockwise direction. Simultaneously, roller 27 on pawl 24 engaging ratchet 23 on roll 1 of the pair of rolls advanced toward the exit end of the rewinding area B rides up on end 123^a of track 123, releasing this roll 1, so that immediately the succeeding pair of rolls begin to traverse the curtain rewinding area B, roll 1 of the pair of rolls at the exit end of the rewinding area B begins to roll up the curtain 3 stretched across said rewinding area.

The position of the actuator blocks 70, 71 at the exit ends of the display and rewinding areas A and B is illustrated by actuator block 70 in Figure 5. To facilitate comprehension of this action, attention is invited to Figure 9 wherein it is seen that the actuator block arms 82 are held perpendicular or in alignment therewith when the latter are in transit with the roll carriages across the display and rewinding areas A and B, by means of the upright bars 96 and 98, which provide tracks intermediate which the rollers 84 and 87 run. The actuator block arms 82, at the end of the upright bars 98, swing laterally inwardly as shown under tension of springs 92 to clear trunnion rollers 30, and permit the latter to be carried or propelled past the ends of detents 115 which subsequently swing back under said trunnions 30 and retain the roll carriages.

The roll carriages after having traversed the curtain display and rewinding areas A and B about the roll carriages at the exit ends of the display and rewinding areas A and B and propel the adjoining roll carriages around through said magazine spaces, there being just sufficient clearance in the magazine spaces to allow free shifting of the roll carriages.

Attention is also directed to the fact that pawls 24 retaining the ratchets 23 on rolls 1 are released when said rolls are advancing from the exit end of the curtain rewinding area round through the upper magazine space and downwardly across the curtain display area to substantially a point where the roll carriages are discharged into the lower magazine space. This enables the rolls 1 to rotate and perform a give and take action on the curtains 3, and also to prevent excessive wear of the ratchets and pawls and to prevent noise, which would result if these parts were permitted to coact while traversing these spaces. For similar reasons rolls 2 are released while travelling from points just above

the entrance to the display area A downwardly and around through the lower magazine space to the entrance of the curtain rewinding area B.

5 The cycle of actions described are identical with respect to transit and timing operations of the several pairs of rolls, which thus travel through a closed cycle of movement.

10 Thus it will be observed that the pairs of rolls in traversing the curtain display area A unroll one curtain out over the said display area while the curtain therebelow is being simultaneously wound up. Since these curtain unrolling and rolling up actions, take place behind bars 16 which conceal the actions of the curtain rolls from view, when viewed from the display area, the illusion that one curtain disappears into the other is produced and the inherent blending of the 15 advertising or other display matter on the curtains 3 makes a most fascinating spectacle.

20 The manner in which the illusion bars 16 traverse the display area A in one direction only and whereby these bars, all of which are identical, enter the display area A and traverse the same one after the other, produces most novel effect and one which enables the observer to read the subject matter on the curtains in a customary direction or manner of 25 reading.

30 By utilization of anti-friction rollers on the roll carriage actuating means and on the latter, and by balancing the weight of said roll carriages by having the rolls 1 and 2 thereof arranged axially in a plane intersecting the centers of the front and rear track runs and tangential with the pitch diameters of sprockets 57, 58, 59 and 60, a balanced and very uniform operating machine is provided.

35 Furthermore, the arrangement whereby the curtain display and rewinding areas A and B are disposed in spaced relation provides a space intermediate the same to accommodate for very effective and simple illuminating means.

40 The foregoing analysis will so fully reveal the gist of this invention, that others can, by applying current mechanical knowledge, readily adapted it to various applications 45 without omitting certain features of the generic or specific aspects of this invention, and therefore all such adaptations should and are intended to be comprehended within the meaning and range of equivalency of the following claims.

50 What I claim is:

1. In a display machine, the combination 55 of a plurality of pairs of rolls; a carriage for each pair of rolls movable in a closed cycle of movement to carry said pairs of rolls intermittently from starting position in one path across a display area and in a return path remote from the display area back to starting position; curtains connecting the 60 rolls of said pairs of rolls in a closed series;

timed mechanism for actuating said carriages intermittently across the display area and the return path; and timed mechanism to effect unrolling of the curtain from the first roll of a pair of rolls moving across the display area and rolling up the curtain previously unrolled on the second roll of the pair of rolls moving across the display area and effecting reverse curtain rolling and unrolling operations during movement of the pairs of rolls in the return path whereby the curtains are rolled on the first roll of the pair of rolls moving to starting position.

2. In a display machine, the combination 70 of a plurality of pairs of rolls; a carriage for each said pair of rolls movable in a closed cycle of movement to carry said pairs of rolls intermittently from starting position in one path across a curtain display area and in a return path across a curtain rewinding area 75

80 back to starting position; curtains connecting the rolls of said pairs of rolls in a closed series; timed mechanism to advance said carriages one by one across the curtain display and rewinding areas and intermittently hold said carriages at the extremities and exits of the curtain display and rewinding areas; and timed mechanism to effect unrolling of the curtain from the first roll of the pair of 85

rolls moving across the display area and rolling up the curtain previously unrolled on the second roll of the pair of rolls moving across the display area and effecting reverse curtain rolling and unrolling operations during movement of the pairs of rolls across the curtain rewinding area whereby the curtains are rolling on the first roll of the pairs of rolls moving to starting position.

90 3. In a display machine, the combination 95 of a plurality of pairs of rolls; a carriage for each said pair of rolls movable in a closed cycle of movement to carry said pair of rolls intermittently from starting position in one path across a display area and in a return path remote from said display area back to starting position; curtains connecting the rolls of said pairs of rolls in closed series; timed mechanism for moving said carriages across the display area and return path; means tending to wind said rolls; and timed means for holding said rolls from winding, said timed means holding the first roll of the pair of rolls preceding that pair of rolls moving across the display area from winding and whereby the second roll of the pair of rolls moving across the display area is free to wind and one curtain is being unrolled from one roll of the pair of rolls moving across the display area and the curtain previously displayed is being rolled on the second roll of the pair of rolls moving across the display area.

100 4. In a display machine, the combination 105 of a plurality of pairs of rolls; a carriage for each said pair of rolls, said carriages being

110

115

120

125

movable in a closed cycle of movement to move said pairs of rolls intermittently from a starting position in a path across a display area and in a return path remote from the display area back to starting position; curtains connecting the rolls of said pairs of rolls in a closed series; timed mechanism for intermittently moving said carriages across the display area and return path; means to 5 wind said rolls; and timed means to hold said rolls from winding, said timed means holding the first roll of the pair of rolls at the exit of the display area whereby the second roll of the succeeding pair of rolls is 10 free to roll up the curtain supported thereby and by aforesaid first roll.

5. In a display machine, the combination of a plurality of pairs of rolls; a carriage for each said pair of rolls; said carriage 20 being movable in a closed cycle of movement to move said pair of rolls one by one in intermittent timed relation from a starting position in a path across a display area and in a return path remote from said display area 25 back to starting position; curtains connecting the rolls of said pairs of rolls in a closed series; means to advance said carriages one by one in intermittent timed relation across said display area and said return path; and 30 means to wind said rolls; and means to control rotation of said rolls, said means locking the first roll of a pair of rolls substantially immediately it has stopped after having traversed the display area whereby the second roll of the preceding pair of rolls is free to 35 roll up the curtain extending and between the first roll aforesaid.

6. In a display machine, the combination of a plurality of pairs of rolls; a carriage 40 for each said pair of rolls; said carriages being movable in a closed cycle of movement to move said pairs of rolls one by one from starting position in intermittent timed relation across a display area and in a return path 45 remote from said display area back to starting position; curtains connecting the rolls of said pairs of rolls in a closed series; mechanism to move said carriages intermittently across said display area and return path; winding means for said rolls; and timing 50 means controlling rotation of said rolls to lock the first roll of a pair of rolls substantially at the moment travel of the same is terminated at the exit of the display area and to hold said rolls locked until the same are moved across the return path and to release said rolls immediately before travel of 55 said rolls is terminated at the exit of the return path.

7. In a display machine, the combination of a plurality of rolls; a carriage for each said 60 pair of rolls; said carriages being movable in a closed cycle of movement to move said pairs of rolls one by one from starting position in intermittent timed relation across a display area and in a return path remote from said display area back to starting position; curtains connecting the rolls of said pairs of 65

rolls in a closed series; mechanism to move said carriages intermittently across said display area and return path; winding means for said rolls; and timing mechanism controlling rotation of said roll to release the first roll of a pair of rolls disposed at the exit of the return path whereby the curtain extending between said first roll and the second roll of a succeeding pair of rolls is free to roll up on said first roll.

8. In a display machine, the combination of a plurality of pairs of rolls; a carriage for each said pair of rolls; said carriages being movable in a closed cycle of movement to move said pairs of rolls one by one from starting position in intermittent timed relation across a display area and in a return path remote from said display area back to starting position; curtains connecting the rolls of said pairs of rolls in a closed series; mechanism to move said carriages intermittently across said display area and return path; winding means for said rolls; and timing mechanism controlling rotation of said rolls to release the first roll of a pair of rolls substantially at the exit of said return path and hold said first roll released until it has again moved across and is stopped at the exit of the display area.

9. In a display machine, the combination of a plurality of pairs of rolls; a carriage for each said pair of rolls; said carriages being movable in a closed cycle of movement to move said pairs of rolls one by one from starting position in intermittent timed relation across a display area and in a return path remote from said display area back to starting position; curtains connecting the rolls of said pairs of rolls in a closed series; mechanism to move said carriages intermittently across said display area and return path; winding means for said rolls; and timing mechanism to control rotation of said rolls to lock the first roll of each pair of rolls substantially at the moment travel of the same is terminated at the exit of the display area and to hold said rolls locked until the same are moved across the return path and to release said rolls immediately before travel of said rolls is terminated at the exit of the return path.

10. In a display machine, the combination of a plurality of pairs of rolls; a carriage for each said pair of rolls; said carriages being movable in a closed cycle of movement to move said pairs of rolls one by one from starting position in intermittent timed relation across a display area and in a return path remote from said display area back to starting position; curtains connecting the rolls of said pairs of rolls in a closed series; mechanism to move said carriages intermittently across said display area and return path; winding means for said rolls; and timing mechanism controlling rotation of said rolls

to lock the second roll of a pair of rolls disposed at the entrance to the return path whereby the curtain extending between said second roll and the first roll of a preceding 5 pair of rolls is free to roll up on said first roll.

11. In a display machine, the combination of a plurality of pairs of rolls; a carriage for each said pair of rolls; said carriages being 10 movable in a closed cycle of movement to move said pairs of rolls one by one from starting position in intermittent timed relation across a display area and in a return path remote from said display area back to starting 15 position; curtains connecting the rolls of said pairs of rolls in a closed series; mechanism to move said carriages intermittently across said display area and return path; winding means for said rolls; and timed 20 mechanism to control rotation of said rolls to lock the second roll of a pair of rolls disposed at the entrance to the return path immediately after said roll has started to move across the return path and to hold said roll 25 locked until the same has traversed the return path and to release the same immediately before travel of the said roll has terminated in its approach to the display area.

12. In a display machine, the combination 30 of a plurality of pairs of rolls; a carriage for each said pair of rolls; said carriages being movable in a closed cycle of movement to move said pairs of rolls one by one from starting position in intermittent timed relation 35 across a display area and in a return path remote from said display area back to starting position; curtains connecting the rolls of said pairs of rolls in a closed series; mechanism to move said carriages intermittently 40 across said display area and return path; winding means for said rolls; and timed mechanism to control rotation of said rolls to release the second roll of each pair of rolls 45 immediately before said roll has stopped at the entrance to the display area, and to hold said roll released until it has traversed the display area and is advanced to stopped position at the entrance to the return path.

13. In a display machine, the combination 50 of a plurality of pairs of rolls; a carriage for each said pair of rolls movable in a closed cycle of movement to carry said pairs of rolls from starting position in one direction across a display area and in a return path remote 55 from said display area back to starting position; a spring to wind each said roll, the spring of the first roll of each said pair of rolls exerting greater winding torque than the spring of the second roll of each pair of 60 rolls so that the first roll of each pair of rolls is under high winding tension and the second roll of each pair of rolls is under low winding tension; curtains connecting the rolls of said pairs of rolls in a closed series; 65 timed mechanism for moving said carriages

intermittently across the display area and return path; and timed mechanism to effect unrolling of the curtain from the high tensioned roll of the pair of rolls moving across the display area and rolling up of the curtain previously unrolled on the low tensioned roll of the pair of rolls moving across the display area and effecting reverse rolling and unrolling operations during movement of the pairs of rolls in the return path whereby the curtains are rolled on the high tensioned roll of the pairs of rolls moving to starting position. 70

14. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed means for holding said rolls from winding, said timed means holding the high tensioned roll of the pair of rolls preceding the pair of rolls moving across the display area from winding whereby the low tensioned roll of the pair of rolls moving across the display area is free to wind and one curtain is being unrolled from the high tensioned roll and the curtain previously displayed is being rolled up on the low tensioned roll of the pair of rolls moving across the display area. 75

15. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of rolls is under low tension; curtains connecting the rolls of said pairs in a closed series; timed mechanism for moving said carriages intermittently across the display area and return path; and timed mechanism to hold said rolls from winding; said timed mechanism holding the high tensioned roll of the pair of rolls at the exit of the display whereby the low tensioned roll of the 80

succeeding pair of rolls is free to roll up the curtain supported thereby and by the aforesaid high tensioned roll.

16. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to release the first roll of a pair of rolls disposed at the exit of the return path whereby the curtain extending between said high tensioned roll and the low tensioned roll of a succeeding pair of rolls is free to roll up on said high tensioned roll.

17. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to lock the high tensioned roll of a pair of rolls moving across the return path whereby the curtain interconnecting said roll and the low tensioned roll of the succeeding pair of rolls may be unrolled from off of said low tensioned roll.

18. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than

the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to release the first roll of a pair of rolls disposed at the exit of the return path whereby the curtain extending between said high tensioned roll and the low tensioned roll of a succeeding pair of rolls is free to roll up on said high tensioned roll.

19. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and means to control rotation of said rolls, said means locking the high tensioned roll of each said pair of rolls substantially immediately after said roll has stopped after having traversed the display area whereby the low tensioned roll of each succeeding pair of rolls is free to roll up the curtain extending therebetween and each high tensioned roll aforesaid.

17. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to release the high tensioned roll of a pair of rolls substantially at the exit of said return path and hold said high tensioned roll released until it has again moved across and is stopped at the exit of the display area.

20. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to lock the high tensioned roll of each pair of rolls substantially at the moment travel of the same is terminated at the exit of the display area and to hold said high tensioned rolls locked until the same are moved across the return path.

and to release said high tensioned rolls immediately before travel of said high tensioned rolls is terminated at the exit of the return path.

21. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to release the low tensioned roll of each pair of rolls immediately before said rolls have stopped at the entrance to the display area, and to hold said rolls released until they have traversed the display area and are advanced to stopped position at the entrance to the return path.

22. In a display machine, the combination of a plurality of pairs of rolls; a carriage for each pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low tensioned roll of a pair of rolls disposed at the entrance to the return path whereby the curtain extending between said low tensioned roll and the high tensioned roll of a preceding pair of rolls is free to roll up on said high tensioned roll.

23. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to control rotation of said rolls to lock the low tensioned roll of a pair of rolls disposed at the entrance to the return path and to hold said roll locked until the same has traversed the return path and to release the same immediately before travel of said roll has terminated in its approach to the display area.

24. In a display machine, the combination of a plurality of pairs of rolls; a carriage for each said pair of rolls movable in a closed cycle of movement to carry said pairs of rolls from starting position in one direction across a display area and in a return path remote from said display area back to starting position; a spring to wind each said roll, the spring of the first roll of each said pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to effect unrolling of the curtain from the first roll of the pair of rolls moving across the display area and rolling up the curtain previously unrolled on the second roll on the pair of rolls moving across the display area and effecting reverse curtain rolling and unrolling operations during movement of the pairs of rolls in the return path whereby the curtains are rolled on the first roll of the pairs of rolls moving to starting position; and means traveling with said pairs of rolls across the display area to conceal from sight the unrolling and rolling up actions of said rolls, when viewed from the display area.

25. In a display machine, the combination of a plurality of pairs of curtain rolls; a carriage for each pair of curtain rolls movable in a closed cycle of movement to carry said pairs of rolls from starting position in one direction across a display area and in a return path remote from said display area back to starting position; a spring to wind each said roll, the spring of the first roll of each pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to effect unrolling of the curtain from the high tensioned roll of the pair of rolls moving across the display area and rolling up the curtain pre-

26. In a display machine, the combination of a plurality of pairs of curtain rolls; a carriage for each pair of curtain rolls movable in a closed cycle of movement to carry said pairs of rolls from starting position in one direction across a display area and in a return path remote from said display area back to starting position; a spring to wind each said roll, the spring of the first roll of each pair of rolls exerting greater winding torque than the spring of the second roll of each pair of rolls so that the first roll of each pair of rolls is under high winding tension and the second roll of each pair of said rolls is under low winding tension; curtains connecting the rolls of said pairs of rolls in a closed series; timed mechanism for moving said carriages intermittently across the display area and return path; and timed mechanism to effect unrolling of the curtain from the high tensioned roll of the pair of rolls moving across the display area and rolling up the curtain pre-

viously unrolled on the low tensioned roll of the pair of rolls moving across the display area and effecting reverse rolling and unrolling operations during movement of the 5 pairs of rolls in the return path whereby the curtains are rolled on the high tensioned roll of the pairs of rolls moving to starting position; and means traveling with said pairs of rolls across the display area to conceal from sight the unrolling and rolling up action of the curtains on said rolls, when viewed from the display area.

26. In a display machine, the combination of a plurality of pairs of rolls; a carriage for each pair of rolls movable in a closed cycle of movement to carry said pairs of rolls intermittently from starting position in one path across a display area and in a return path remote from the display area back to starting 20 position; curtains connecting the rolls of said position of rolls in a closed series; timed mechanism for actuating said carriages intermittently across the display area and return path; timed mechanism to effect unrolling of 25 the curtain from the first roll of the pair of rolls moving across the display area and rolling up the curtain previously unrolled on the second roll of the pair of rolls moving across the display area and effecting reverse curtain 30 rolling and unrolling operations during movement of the pairs of rolls in the return path whereby the curtains are rolled on the first roll of the pairs of rolls moving to starting 35 position; and means on each said carriage arranged forwardly of said rolls to conceal curtain unrolling and rolling up actions from view, when viewed from the display area.

27. In a display machine, the combination of a plurality of pairs of rolls; a carriage for 40 each pair of rolls movable in a closed cycle of movement to carry said pairs of rolls from starting position in one direction across a display area and in a return path remote from said display area back to starting position; a spring to wind each roll, the spring of the first roll of each pair of rolls exerting greater winding torque than the spring of the second roll of each pair of rolls so that the first roll of each pair of rolls is under 45 high winding tension and the second roll of each pair of rolls is under low winding tension; curtains connecting the rolls of said pairs of rolls in a closed series; timed mechanism for moving said carriages intermittently across the display area and the return path; timed mechanism to effect unrolling of 50 the curtain from the high tensioned roll of the pair of rolls moving across the display area and rolling up the curtain previously unrolled on the low tensioned roll of the pair of rolls moving across the display area and effecting reverse rolling and unrolling curtain operations during movement of the pairs of rolls in the return path whereby the curtains are rolled on the high tensioned roll

of the pairs of rolls moving to starting position; and means traveling with said pairs of rolls across the display area to conceal from sight the unrolling and rolling up actions of the said curtains, when viewed from the display area.

28. In a display machine, the combination of a plurality of pairs of rolls; a carriage for each said pair of rolls; a curtain mounted on one of the rolls of each pair of rolls to unroll therefrom during movement of the pair of rolls across a display area and to roll up the second roll of the following pair of rolls when the latter pair of rolls is moving across the display area, whereby one curtain unrolls and another curtain rolls up in the same direction; means for actuating and timing the actuation of said carriages and the winding of said rolls.

29. In a display machine, the combination of a plurality of pairs of rolls; a carriage for each said pairs of rolls; a curtain mounted on one of the rolls of each pair of rolls to unroll therefrom during movement of the pair of rolls across a display area and to roll up the second roll of the following pair of rolls when the latter pair is moving across the display area, whereby one curtain unrolls and another curtain rolls up in the same direction and in substantially the same plane; means to wind said rolls; and means for actuating and timing the actuation of said carriages and winding of said rolls.

30. In a display machine the combination of a plurality of pairs of rolls; a carriage for each said pair of rolls; a curtain mounted on one of the rolls of each said pair of rolls to unroll therefrom during movement of the pair of rolls across a display area and to roll up the second roll of the following pair of rolls when the latter pair is moving across the display area, whereby one curtain unrolls and another curtain rolls up in the same direction; means for actuating and timing the actuation of said carriages and the winding of said rolls; and means traveling with said pairs of rolls to conceal from sight curtain unrolling and rolling up actions, when viewed from the display area.

31. In a display machine, the combination of a plurality of pairs of rolls; a carriage for each said pair of rolls; a curtain mounted on one of the rolls of each pair of rolls to unroll therefrom during movement of the pair of rolls across a display area and to roll up the second roll of the following pair of rolls when the latter is moving across the display area, whereby one curtain unrolls and another curtain rolls up in the same direction in substantially the same plane; means to wind said rolls; means for actuating and timing the actuation of said carriages and the winding and unwinding of said rolls; and means on each said carriage arranged forwardly of said rolls in a plane parallel to

the plane in which said curtains are disposed across the display area to conceal curtain unrolling and rolling up actions from view, when viewed from the display area.

32. In a display machine, the combination of a plurality of pairs of rolls; a carriage for each said pair of rolls; timed actuating mechanism for moving said carriages intermittently across a display area and for holding them at the entrance to and the exit of the display area; a curtain normally wound on one of the rolls on each said pair of rolls and connected to the second roll of the succeeding pair of rolls; means for winding said rolls controlled by said timed actuating mechanism; and mechanism for controlling and timing the winding and unwinding actions of said rolls.

33. In a display machine, the combination of a plurality of pairs of rolls movable intermittently and consecutively across a display area in one direction; conveying means for said pairs of rolls; a curtain normally wound on one roll on said pairs of rolls and connected at its end to the second roll of the next succeeding pair of rolls; mechanism for actuating and timing the movement of said roll conveying means; and mechanism for timing the winding and unwinding actions of said rolls.

34. In a display machine, the combination of a plurality of pairs of rolls movable intermittently and consecutively across a display area in one direction; conveying means for said pairs of rolls; a curtain normally wound on one roll of said pairs of rolls and connected at its end to the second roll of the next succeeding pair of rolls; mechanism for actuating and timing the movement of said roll conveying means and the winding and unwinding of said rolls; and means traveling with said rolls across the display area to conceal from sight unrolling and rolling up actions of said curtains, when viewed from the display area.

35. In a display machine, the combination of a plurality of pairs of rolls movable intermittently and consecutively across a display area in one direction; conveying means for each said pair of rolls; a curtain normally wound on one roll of said pairs of rolls and connected at its end to the second roll of the next succeeding pairs of rolls; mechanism for actuating and timing the movement of said roll conveying means and the winding and unwinding actions of said rolls; and means carried by each said roll conveying means arranged forwardly of said rolls to conceal curtain rolling up and unrolling actions from view, when viewed from the display area.

36. In a display machine, the combination of a plurality of pairs of rolls movable intermittently and consecutively across a display area in one direction; springs tending to wind said rolls, the spring for one roll being stronger than the spring for the other roll, whereby one roll is under a high tension and the other

roll is under low tension; a curtain wound on each high tensioned roll and connected at its end to the low tensioned roll of the following pair of rolls; mechanism for moving said pairs of rolls across the display area and holding the following and preceding pairs of rolls at the entrance and exit of the display area; means for holding the high tensioned roll of the pair of rolls at the exit of the display area from winding during movement of an intermediate pair of rolls across the display area and whereby the low tensioned roll of the intermediate pair of rolls moving across the display area is free to roll up the curtain connected thereto.

37. In a display machine, the combination of a plurality of pairs of rolls; a supporting carriage for each said pair of rolls; mechanism for moving one of said carriages across a display area in one direction and holding the following and preceding carriages at the entrance and exit of the display area; a curtain mounted on one roll on each said pair of rolls and connected to the other roll of the following pair of rolls; means tending to wind said rolls; and timed means for holding said rolls from winding, said timed means holding the first roll of the pair of rolls preceding that pair of rolls moving across the display area from winding whereby the second roll of the pair of rolls moving across the display area is free to wind and one curtain is being unrolled from one roll of the pair of rolls in the display area, and the curtain previously displayed is being rolled up on the second roll of the pair of rolls moving across the display area.

38. In a display machine, the combination of a plurality of pairs of rolls; a supporting carriage for each said pair of rolls; mechanism for moving one of said carriages across a display area in one direction and holding the following and preceding carriages stationary at the entrance and exit of the display area; a curtain mounted on one roll of each pair of rolls and connected to the other roll of the following pair of rolls; means tending to wind said rolls; and timed means for holding said rolls from winding; said timed means holding the first roll of the pair of rolls preceding that pair moving across the display area from winding whereby the second roll of the pair of rolls moving across the display area is free to wind, and one curtain is being unrolled from one roll of the pair of rolls in the display area and the curtain previously displayed is being rolled

upon the second roll of the pair of rolls unwinding in the same direction as the winding movement of the other roll.

39. In a display machine, the combination of a plurality of pairs of rolls; a supporting carriage for each said pairs of rolls; springs tending to wind said rolls, the spring of the

first roll of each pair of rolls being stronger than the spring of the second roll, whereby the first roll is under high tension and the second roll is under low tension; means carried by said carriages for holding said rolls from winding by their springs; stationary means arranged in the path of movement of said holding means for releasing said holding means at predetermined intervals; a curtain 10 normally wound on the high tensioned roll of one pair of rolls and connected to the low tensioned roll of the next following pair; mechanism moving said pairs of rolls consecutively across a display area 15 and holding the following and preceding pairs of rolls at the entrance and exit of the display area; said holding means holding the high tensioned roll of the pair of rolls at the exit of the display area from winding 20 whereby the low tensioned roll is free to roll up the curtain connected thereto during movement of the pair of rolls across the display area; and means for timing the actuation and stopping of said carriages.

40. In a display machine, the combination of a plurality of pairs of rolls; a carriage for each said pair of rolls; mechanism for moving said carriages consecutively and intermittently across a predetermined space and 25 for holding said carriages at the beginning and end of said space while the intermediate carriage is moving across said space; a curtain connected to one roll of each said pair of rolls and the second roll of the preceding pair of rolls, the curtain being wound up on the second roll of the preceding pair of rolls whereby it unwinds therefrom during movement of the intermediate pair of rolls across said space; means tending to turn said rolls 30 to wind said curtains thereon; and means for holding the second roll of the preceding pair of rolls from winding movement during travel of the preceding pair of rolls across said space after the intermediate pair of rolls 35 has traversed said space whereby the first roll of the intermediate pair of rolls winds the curtain thereon as the preceding pair of rolls traverses said space towards the intermediate pair of rolls.

41. In a display machine, the combination of a plurality of pairs of rolls; a carriage for each said pair of rolls; mechanism for moving said carriages consecutively and intermittently across an open space and for holding the carriages at the beginning and end of the open space while an intermediate carriage is moving across said open space; a spring tending to wind each said roll, the 45 spring for one roll being stronger than that for the other whereby one roll is under high tension and the other under low tension; a curtain connected to the low tension roll of each pair and the high tension roll of the next preceding pair, the curtain being wound

on the low tension roll of the pair at the entrance of the open space and unwinding therefrom as the intermediate pair traverses said open space and thereby being unwound from the low tension roll when the intermediate pair has traversed said open space; means for holding the high tension roll from winding movement while traversing said open space; means for releasing said holding means after the high tension roll has traversed said open space whereby the high tension roll rolls up the curtain stretched across said open space between the high tension and low tension rolls of the different pair of rolls.

42. In a display machine, in combination, 50 a frame structure embodying two endless tracks disposed in parallel spaced relation, each said track including parallel front and rear runs connected by substantially semi-circular end runs; carriages extending between and supported by said tracks; a pair of rolls supported by each carriage escapement means for retaining said carriages about said end runs of said tracks; curtains interconnecting the adjoining rolls of each of said pair of rolls so that all of said rolls are interconnected by said curtains; conveyor means to actuate said escapement means to successively release said carriages from about said end runs, convey the same across said front and rear runs and discharge the same into said end runs; and timed means to control actuation of said carriages and winding and unwinding actions of said rolls to effect unrolling of the curtain from the first roll of the pair of rolls moving across the front runs of said tracks and rolling up the curtain previously unrolled, on the second roll of the pair of rolls moving across the front runs of said tracks and effecting reverse curtain rolling and unrolling actions during movement of the pairs of rolls in the rear runs of said tracks whereby said curtains are rolled on the first roll of each pair of rolls advancing around said end runs toward said front runs.

43. In a display machine, in combination, 105 a frame structure, embodying two endless tracks disposed in parallel spaced relation, each said track including front and rear runs connected by substantially semi-circular end runs; escapement means supported by said frame structure extending into the front and rear runs of said tracks in close proximity to the points of connection of said end runs with said front and rear runs providing magazines in said end runs between said escapement means; carriages extending between, supported by and adapted to be traversed about said endless tracks, nested in said magazines; a pair of rolls carried by each said carriage; curtains interconnecting the adjoining rolls of each said pair of rolls; conveyor means coacting with said escapement means to actuate the same and release 110

said carriages from about said end runs, convey the same across said front and rear runs and discharge the same into said end runs; winding means for said rolls; and timing means to control actuation of said carriages and winding and unwinding actions of said rolls to effect unrolling of the curtain from the first roll of the pair of rolls moving across the front runs of said tracks and rolling up the curtain previously unrolled, on the second roll of the pair of rolls moving across the front runs of said tracks and effecting reverse curtain rolling and unrolling actions during movement of the pair of rolls in the rear runs of said tracks whereby said curtains are rolled on the first roll of the pairs of rolls advancing around said end runs towards said front runs.

44. In a display machine, in combination, a frame structure embodying two endless tracks disposed in parallel spaced relation, each said track including parallel front and rear runs interconnected by substantially semi-circular end runs; carriages extending between and supported by said tracks; escapement means for retaining said carriages about the end runs of said tracks; a pair of rolls supported by each of said carriages; a spring to wind up each roll of said pairs of rolls, the spring in the first roll of each pair of rolls exerting a greater winding torque than the spring of the second roll of each pair of rolls so that the first roll of each pair of rolls is high tensioned and the second roll of each pair of rolls is low tensioned; curtains interconnecting the adjoining rolls of said pairs of rolls; conveyor means coacting with said escapement means to actuate the same to successively release said carriages from about said end runs, convey the same across said front and rear runs and discharge the same into said end runs; and timed means to control winding and unwinding operations of said rolls to effect unrolling of a curtain from the high tensioned roll of a pair of rolls moving across the front runs of said tracks and rolling up of a curtain previously unrolled on the low tensioned roll of a pair of rolls moving across the front runs of said tracks and effecting reverse curtain rolling and unrolling actions during movement of said pairs of rolls in the rear runs of said tracks whereby said curtains are rolled on the high tensioned roll of the pairs of rolls advancing around said end runs toward the front runs of said track.

45. In a display machine, in combination, a frame structure embodying two endless tracks disposed in parallel spaced relation, each said track including parallel front and rear runs interconnected by substantially semi-circular end runs; escapement means supported by said frame structure extending into said front and rear runs of both said tracks in close proximity to the connecting

points of said end runs with said front and rear runs, providing magazines in said end runs and the ends of said front and rear runs intermediate said escapement means; carriages extending between, supported by and adapted to be traversed about said endless tracks, nested in said magazines, sprockets journaled in pairs on said frame structure intermediate said magazines; a conveyor chain trained over each said pair of sprockets; actuator blocks on said conveyor chains to actuate said escapement means, release said carriages in intermittent time relation from said magazine, traverse same across said front and rear runs of said tracks and discharge same into said magazines; a pair of rolls carried by each said carriage; curtains interconnecting the opposed rolls of said pairs of rolls so that all of said pairs of rolls are interconnected by said curtains; winding means for said rolls; and timed means to control rotation of said rolls to effect unrolling of the curtain from the first roll of the pair of rolls moving across the front runs of said tracks and rolling up the curtain previously unrolled on the second roll of the pair of rolls moving across the front runs of said tracks and effecting reverse curtain rolling and unrolling operations during movement of a pair of rolls in the rear runs of said tracks whereby said curtains are rolled on the first roll of the pairs of rolls advanced around said end runs toward said front runs.

46. In a display machine, in combination, a frame structure embodying two endless tracks disposed in spaced parallel relation, each said tracks including parallel front and rear runs connected by substantially semi-circular end runs; escapement means supported by said frame structure extending into said front and rear runs of both said tracks in close proximity to the points of connection of said end runs with said front and rear runs, providing a magazine at each end of said track in said end runs intermediate said escapement means; carriages extending between, supported by and adapted to be traversed about said endless tracks, nested in said magazines; sprockets journaled in pairs on said frame structure intermediate said magazines; a conveyor chain trained over each said pair of sprockets and extending therebetween in parallel relation with the front and rear runs of said tracks; actuator blocks on said conveyor chains to actuate said escapement means, engage and release said carriages in intermittent timed relation from said magazines, traverse same across said front and rear runs of said tracks and discharge same into said magazines; a pair of rolls carried by each said carriage; curtains interconnecting the opposed rolls of said pairs of rolls so that all of said pairs of rolls are interconnected by said curtains; a spring to wind up after said roll, the spring

in the first roll of each said pair of rolls exerting greater winding torque than the spring in the second roll of each pair of rolls so that the first roll of each said pair of rolls is high tensioned and the second roll of each pair of rolls is low tensioned; and timed means to control winding and unwinding actions of said rolls to effect unrolling of the curtain from the high tensioned roll of the pair of rolls moving across the front runs of said tracks and rolling up the curtain previously unrolled on the low tensioned roll of the pair of rolls moving across the front runs of said tracks and effecting reverse curtain rolling and unrolling actions during movement of said pairs of rolls in the rear runs of said tracks whereby said curtains are rolled on the high tensioned roll of the pairs of rolls advanced around said end runs toward the front runs of said tracks.

47. In a display machine, in combination, a frame structure embodying two endless tracks disposed in parallel spaced relation, each said track including parallel front and rear runs connected by substantially semi-circular end runs; carriages extending between and supported by said tracks; a pair of rolls supported by each carriage; escapement means for retaining said carriages about said end runs of said tracks; curtains interconnecting the adjoining rolls of each said pair of rolls so that all of said rolls are interconnected by said curtains; conveyor means to actuate said escapement means to successively release said carriages from about said end runs, convey the same across said front and rear runs and discharge the same into said end runs; and timing means controlling actuation of said carriages and winding and unwinding actions of said rolls to effect unrolling of the curtain from the first roll of the pair of rolls moving across the front runs of said tracks and rolling up the curtain previously unrolled, on the second roll the pair of rolls moving across the front runs of said tracks and effecting reverse curtain rolling and unrolling actions during movement of the pairs of rolls in the rear runs of said tracks whereby said curtains are rolled on the first roll of the pair of rolls advancing around said end runs toward said front runs; and means carried by each said carriage disposed immediately forward of said pairs of rolls to conceal the unrolling and rolling action of said curtains from view.

48. In a display machine, in combination, a frame structure embodying two endless tracks disposed in parallel spaced relation each said tracks including front and rear runs connected by substantially semi-circular end runs; escapement means supported by said frame structure extending into the front and rear runs of said tracks in close proximity to the points of connection of said end runs

with said front and rear runs, providing magazines in said end runs between said escapement means; carriages extending between, supported by and adapted to be traversed about said endless tracks, nested in said magazines; a pair of rolls carried by each said carriage; curtains interconnecting the adjoining rolls of each said pair of rolls; conveyor means coacting with said escapement means to actuate the same successively to release said carriage from about said end runs, convey the same across said front and rear runs and discharge the same into said end runs; winding means for said rolls; and timing means to control actuation of said carriages and winding and unwinding actions of said rolls to effect unrolling of the curtain from the first roll of the pair of rolls moving across the front runs of said tracks and rolling up the curtain previously unrolled, on the second roll of the pair of rolls moving across the front runs of said tracks and effecting reverse curtain rolling and unrolling actions during movement of the pair of rolls in the rear runs of said tracks whereby said curtains are rolled on the first roll of the pairs of rolls advancing around said end runs towards said front runs; and means carried by each said carriage disposed immediately forward of said pairs of rolls to conceal the unrolling and rolling action of said curtains from view.

49. In a display machine, in combination, a frame structure embodying two endless tracks disposed in parallel spaced relation, each said track including parallel front and rear runs interconnected by substantially semi-circular end runs; carriages extending between and supported by said tracks; escapement means for retaining said carriages about the end runs of said tracks; a pair of rolls supported by each said carriage; a spring to wind up each roll of said pairs of rolls, the spring in the first roll of each pair of rolls exerting a greater winding torque than the spring of the second roll of each pair of rolls so that the first roll of each pair of rolls is high tensioned and the second roll of each pair of rolls is low tensioned; curtains interconnecting the adjoining rolls of said pairs of rolls; conveyor means coacting with said escapement means to actuate the same to successively release said carriages from about said end runs, convey the same across said front and rear runs and discharge the same into said end runs; and timed means to control winding and unwinding operations of said rolls to effect unrolling of a curtain from the high tensioned roll of a pair of rolls moving across the front runs of said tracks and rolling up of a curtain previously unrolled on the low tensioned roll of the pair of rolls moving across the front runs of said tracks and effecting reverse curtain rolling and unrolling actions during movement

of said pairs of rolls in the rear runs of said tracks whereby said curtains are rolled on the high tensioned roll of the pairs of rolls advancing around said end runs toward the front runs of said track; and means carried by each said carriage disposed immediately forward of said pairs of rolls to conceal the unrolling and rolling up actions of said curtain from view.

50. In a display machine, in combination, a frame structure embodying two endless tracks disposed in parallel spaced relation, each said track including parallel front and rear runs interconnected by substantially semi-circular end runs; escapement means supported by said frame structure extending in close proximity to the connecting points of said end runs with said front and rear runs, providing magazines in said end runs and the ends of said front and rear runs intermediate said escapement means; carriages extending between, supported by and adapted to be traversed about said endless tracks, nested in said magazines, sprockets journaled in pairs on said frame structure intermediate said magazines, a conveyor chain trained over each said pair of sprockets; actuator blocks on said conveyor chains to actuate said escapement means; release said carriages in intermittent timed relation from said magazines, traverse same across said front and rear runs of said tracks and discharge same into said magazines; a pair of rolls carried by each said carriage; curtains interconnecting the opposed rolls of said pairs of rolls so that all of said pairs of rolls are interconnected by said curtains; a spring to wind up each said roll, the spring in the first roll of each pair of rolls exerting greater winding torque than the spring in the second roll of each pair of rolls so that the first roll of each pair of rolls is high tensioned and the second roll of each pair of rolls is low tensioned; timed means to control winding and unwinding actions of said rolls to effect unrolling of the curtain from the high tensioned roll of the pair of rolls moving across the front runs of said tracks and rolling up the curtain previously unrolled on the low tensioned roll of the pair of rolls moving across the front runs of said tracks and effecting reverse curtain rolling and unrolling actions during movement of said pairs of rolls in the rear runs of said tracks whereby said curtains are rolled on the high tensioned roll of the pairs of rolls advanced around said end runs toward the front runs of said tracks; and means carried by each said carriage disposed immediately forward of said pairs of rolls to conceal the unrolling and rolling up actions of said curtains from view.

51. In a display machine, in combination, a frame structure embodying two endless tracks disposed in spaced parallel relation, each said track including parallel front and rear runs connected by substantially semi-circular end runs; escapement means supported by said frame structure extending into said front and rear runs of both said tracks in close proximity to the points of connection of said end runs with said front and rear runs, providing magazines in said end runs intermediate said escapement means; carriages extending between, supported by and adapted to be advanced about said endless tracks, nested in said magazines; sprockets journaled in pairs on said frame structure intermediate said magazines; a conveyor chain trained over each said pair of sprockets to

said track in said end runs intermediate said escapement means; carriages extending between, supported by and adapted to be traversed about said endless tracks, nested in said magazines; sprockets journaled in pairs on said frame structure intermediate said magazines; a conveyor chain trained over each said pair of sprockets and extending therebetween in parallel relation with the front and rear runs of said tracks; actuator blocks on said conveyor chains to actuate said escapement means; release said carriages in intermittent timed relation from said magazines, traverse same across said front and rear runs of said tracks and discharge same into said magazines; a pair of rolls carried by each said carriage; curtains interconnecting the opposed rolls of said pairs of rolls so that all of said pairs of rolls are interconnected by said curtains; a spring to wind up each said roll, the spring in the first roll of each pair of rolls exerting greater winding torque than the spring in the second roll of each pair of rolls so that the first roll of each pair of rolls is high tensioned and the second roll of each pair of rolls is low tensioned; timed means to control winding and unwinding actions of said rolls to effect unrolling of the curtain from the high tensioned roll of the pair of rolls moving across the front runs of said tracks and rolling up the curtain previously unrolled on the low tensioned roll of the pair of rolls moving across the front runs of said tracks and effecting reverse curtain rolling and unrolling actions during movement of said pairs of rolls in the rear runs of said tracks whereby said curtains are rolled on the high tensioned roll of the pairs of rolls advanced around said end runs toward the front runs of said tracks; and means carried by each said carriage disposed immediately forward of said pairs of rolls to conceal the unrolling and rolling up actions of said curtains from view.

52. In a display machine, in combination, a frame structure embodying two endless tracks disposed in spaced parallel relation, each said track including parallel front and rear runs connected by substantially semi-circular end runs; escapement means supported by said frame structure extending into said front and rear runs of both said tracks in equidistant spaced relation and aligned in pairs in planes at right angle to the front and rear runs of said tracks and disposed in closed proximity to the points of connection of said end runs with said front and rear runs, providing magazines in said end runs intermediate said escapement means; carriages extending between, supported by and adapted to be advanced about said endless tracks, nested in said magazines; sprockets journaled in pairs on said frame structure intermediate said magazines; a conveyor chain trained over each said pair of sprockets to

actuate blocks disposed in equidistant spaced relation on each said conveyor chain adapted to actuate said escapement means, engage and release said carriages in intermittent 5 timed relation from said magazines, advance the same across said front and rear runs of said tracks and discharge the same into magazines; a pair of rolls carried by each said carriage; curtains interconnecting the opposed 10 rolls of said pairs of rolls so that all said pairs of rolls are interconnected by said curtains; winding means for said rolls; and timing means to control the winding and un-winding actions of said rolls to effect unrolling 15 of the curtain from the front roll of the pair of rolls moving across the front runs of said tracks and rolling up the curtain previously unrolled on the second roll of the pair of rolls moving across the front runs of said tracks and effecting reverse curtain rolling and unrolling actions during movement of the pair of rolls in the rear runs of said tracks whereby said curtains are rolled on the first roll of the pairs of rolls advancing around said end runs towards said front runs; and means carried 20 by each said carriage disposed immediately forward of said pairs of rolls to conceal the unrolling and rolling up actions of said curtains from view.

53. In a display machine, in combination, a frame structure including two endless tracks arranged in parallel spaced relation, each said track including parallel front and 30 rear runs connected at their ends by substantially semi-circular end runs; escapement means in the form of articulated detents and motion transmitting levers mounted on said frame structure with said detents extending 35 into said front and rear runs in close proximity to the ends thereof, and in the form of detents mounted on said frame structure and extending into said front and rear runs, opposed to said first mentioned detents and disposed in close proximity to the opposite ends of said front and rear runs, the spaces intermediate said detents about said end runs constituting carriage magazines, carriages 40 extending between, supported by and adapted to be conveyed about said tracks, retained in said magazines by said detents when not in transit across said front and rear track runs; sprockets journaled in pairs on said frame 45 structure intermediate said carriage magazines; a conveyor chain trained over each said pair of sprockets; actuator blocks on said conveyor chains adapted to actuate said motion transmitting levers, simultaneously depress said detents interconnected thereto out of said front and rear track runs and simultaneously couple to and subsequently conveyed carriages into and across both the front and rear runs of said tracks and discharge 50 same into said magazines in intermittent timed relation; a pair of rolls mounted on each said carriage; a spring to wind up each roll of said pair of rolls, the spring of the first roll of each said pair of rolls exerting high winding torque on said roll so that the same is high tensioned and the spring of the second roll of each said pair of rolls exerting low winding torque so that said second rolls 55 are low tensioned; a ratchet on each roll of said pairs of rolls; pawls carried by said carriages tensioned to engage said ratchets to control rotation of said rolls, and means on 60 said frame structure to release said pawls in intermittent timed relation to effect unrolling of the curtains.

to control winding and unwinding actions of said rolls to effect unrolling of the curtain from the first roll of the pair of rolls moving across the front runs of said tracks and rolling up the curtains previously unrolled, on the second roll of the pair of rolls moving across the front runs of said tracks and effecting reverse curtain rolling and unrolling actions during movement of the pairs of rolls in the rear runs of said tracks whereby said curtains are rolled on the first roll of the pairs of rolls advancing around said end runs towards said front runs; and means carried by each said carriage disposed immediately forward of said pairs of rolls to conceal the unrolling and rolling up actions of said curtains from view.

54. In a display machine, in combination, a frame structure including two endless tracks arranged in parallel spaced relation, each said track including parallel front and rear runs connected at their ends by substantially semi-circular end runs; escapement means in the form of articulated detents and motion transmitting levers mounted on said frame structure with said detents extending into said front and rear runs in close proximity to the ends thereof, and in the form of detents mounted on said frame structure and extending into said front and rear runs, opposed to said first mentioned detents and disposed in close proximity to the opposite ends of said front and rear runs, the spaces intermediate said detents about said end runs constituting carriage magazines, carriages extending between, supported by and adapted to be conveyed about said tracks, retained in said magazines by said detents when not in transit across said front and rear track runs; sprockets journaled in pairs on said frame structure intermediate said carriage magazines; a conveyor chain trained over each said pair of sprockets; actuator blocks on said conveyor chains adapted to actuate said motion transmitting levers, simultaneously depress said detents interconnected thereto out of said front and rear track runs and simultaneously couple to and subsequently conveyed carriages into and across both the front and rear runs of said tracks and discharge same into said magazines in intermittent timed relation; a pair of rolls mounted on each said carriage; a spring to wind up each roll of said pair of rolls, the spring of the first roll of each said pair of rolls exerting high winding torque on said roll so that the same is high tensioned and the spring of the second roll of each said pair of rolls exerting low winding torque so that said second rolls are low tensioned; a ratchet on each roll of said pairs of rolls; pawls carried by said carriages tensioned to engage said ratchets to control rotation of said rolls, and means on said frame structure to release said pawls in 70 75 80 85 90 95 100 105 110 115 120 125 130

tain from the first roll of the pair of rolls moving across front runs of said tracks and rolling up the curtains previously unrolled on the second roll of the pair of rolls moving across the front runs of said tracks and effecting reverse curtain rolling and unrolling actions during movement of the pair of rolls in the rear runs of said tracks whereby said curtains are rolled on the first roll 5 of the pair of rolls advancing around said runs toward said front runs; and strips of material carried by each said carriage disposed immediately forward of said pairs of rolls to conceal the unrolling and rolling up 10 actions of said curtains from view.

55. In a display machine, in combination, a frame structure including two endless tracks arranged in parallel spaced relation, each said track including parallel front and 15 rear runs connected at their ends by substantially semi-circular end runs; escapement means in the form of articulated detents and motion transmitting levers mounted on said frame structure with said detents extending 20 into said front and rear runs in close proximity to the end thereof, and in the form of detents mounted on said frame structure and extending into said front and rear runs, opposed to said first mentioned detents and disposed in close proximity to the opposite ends 25 of said front and rear runs, the spaces intermediate said detents about said end runs constituting carriage magazines; carriages extending between, supported by and adapted 30 to be conveyed about said tracks, retained in said magazines by said detents when not in transit across said front and rear track runs; sprockets journaled in pairs on said frame structure intermediate said carriage magazines; a conveyor chain trained over each said pair of sprockets; actuator blocks on said 35 conveyor chains adapted to actuate said motion transmitting levers, simultaneously depress said detents interconnected thereto out of said front and rear runs and simultaneously convey carriages into and across both the front and rear runs of said tracks and into said 40 magazines in intermittent timed relation; a pair of rolls carried by each said carriage; curtains interconnecting the opposed rolls of said pairs of rolls; a spring to wind up each 45 roll of said pair of rolls, the spring of the first roll of each said pair of rolls exerting a high winding torque on said roll so that the same is high tensioned and the spring of the second roll of each said pair of rolls exerting low winding torque so that said second rolls are low tensioned; a ratchet on each 50 roll of said pairs of rolls; pawls carried by said carriages tensioned to engage said ratchets to control rotation of said rolls; tracks on said frame structure in the paths of said pawls to release said pawls from said ratchets in timed relation to effect unrolling 55 of the curtain from the first roll of the pair 60 of rolls moving across the front runs of said tracks and rolling up the curtain previously unrolled on the second roll of the pair of rolls moving across the front runs of said tracks and effecting reverse curtain rolling and rolling and unrolling actions during movement of the pairs of rolls in the rear runs of said tracks whereby said curtains are rolled on the first rolls of said pairs of rolls advancing around said end runs towards said front runs; and a strip of material mounted on each said carriage in front of said rolls.

56. In a display machine, in combination, a frame structure including two endless tracks arranged in parallel spaced relation, each said track including parallel front and rear runs connected at their ends by substantially semi-circular end runs; escapement means in the form of articulated detents and motion transmitting levers mounted on said frame structure with said detents extending into said front and rear runs in close proximity to the ends thereon, and in the form of detents mounted on said frame structure and extending into said front and rear runs, opposed to said first mentioned detents, and disposed in close proximity to the opposite ends of said front and rear runs, the spaces intermediate said detents about said end runs constituting carriage magazines; carriage extending between, supported by and adapted to be conveyed about said tracks, retained in said magazines by said detents when not in transit across said front and rear track runs; sprockets journaled in pairs on said frame structure in spaced relation intermediate said carriage magazines; a conveyor chain trained over each said pair of sprockets; a pair of actuator blocks arranged in equidistant spaced relation on each said conveyor chain adapted to actuate said motion transmitting levers, simultaneously depress said detents interconnected thereto out of said front and rear runs and simultaneously convey carriages into and across both the front and rear runs of said tracks and into said magazines in intermittent timed relation; a pair of rolls carried by each said carriage; curtains interconnecting the opposed rolls of said pairs of rolls; a spring to wind up each roll of said pair of rolls, the springs in the first roll of each said pair of rolls exerting a greater winding torque than the spring of the second roll of each said pair of rolls so that the first roll of each pair of rolls is high tensioned and the second roll of each pair of rolls is low tensioned; a ratchet on each roll of said pairs of rolls; pawls pivoted on said carriages; springs tensioning said pawls to engage the same with said ratchets to control rotation of said rolls; tracks on said frame structure arranged in the paths of said pawls to disengage and permit reengagement of said pawls from and with said ratchets in timed relation with the actuation of said car-

riages to effect unrolling of the curtains from the high tensioned roll of the pair of rolls moving across the front runs of said tracks and rolling up the curtains previously unrolled on the low tensioned roll of the pair of rolls moving across the front runs of said tracks and effecting reverse rolling and unrolling actions during movement of the pair of rolls in the rear runs of said tracks where-
 5 by said curtains are rolled on the high tensioned roll of the pairs of rolls advancing around said end runs toward said front runs of said tracks; means on the low tensioned roll of each said pairs of rolls coacting with
 10 means on said frame structure to align the curtains engaged to said low tensioned rolls tangent with the surfaces of said rolls before the carriages carrying said rolls are released from said carriage magazine and are moving
 15 across the front runs of said tracks; and a strip of material carried by each said carriage in front of said rolls to conceal curtain unrolling and rolling up actions from view.

57. In a machine of the class described, in combination, a frame structure embodying tracks including front and rear runs and interconnecting end runs, carriages movable intermittently along said runs, a pair of rolls supported by each carriage, curtains connect-
 25 ing the rolls of said pairs of rolls in a closed series, actuating mechanism for moving the carriages including endless conveyor means having portions running in parallel relation to front and rear runs of said tracks, the end
 30 runs of said tracks being located beyond the ends of said conveyor means forming accumulating spaces for said carriages between the front and rear runs, mechanism to effect the unrolling of the curtain from the first roll
 35 of a pair of rolls moving along the front track run and rolling up the curtain previously unrolled on the second roll of the pair of rolls moving across the front run and to effect re-
 40 verse curtain rolling and unrolling opera-
 45 tions during the movement of the carriages along the rear track run and means on said conveyor for picking up said carriages at the entrances of said front and rear runs and re-
 50 leasing them at the exits of said front and rear runs.

58. In a machine of the class described, in combination, a frame structure embodying two endless tracks arranged in spaced parallel relation, front and rear runs connected
 55 at their ends by substantially semi-circular end runs, carriages extending between and supported by said tracks, a pair of rolls mounted on each carriage, curtains connect-
 60 ing the rolls of said pairs in a closed series, mechanism to effect unrolling of the curtain from the first roll of the pair of rolls moving across the front run and rolling up the curtain previously unrolled on the second roll of the pair along the front run and effecting
 65 reverse curtain rolling and unrolling opera-

tions during movement of the pairs of rollers in the rear track runs, actuating means for said carriages supported by the frame structure for picking up said carriages at the entrances of the front and rear runs and coacting with said mechanism to successively release the carriages from the front and rear track runs, advance the same across the front and rear ends and discharge the same into the end track runs in intermittent timed relation.

59. In a machine of the class described, in combination, a frame structure embodying two endless tracks arranged in spaced parallel relation, each said track including parallel front and rear runs connected at their ends by substantially semi-circular end runs; carriages extending between and supported by said tracks; sprockets journaled in pairs on said frame structure in spaced relation intermediate said track end runs; conveyor chains trained over each said pair of sprockets; escapement means on said frame structure between said sprockets and the end runs of said tracks, adapted to retain said carriages in said end runs of said tracks when not in transit across the front and rear runs; and means carried by said conveyor chains coacting with said escapement means and said carriages to successively release said carriages from said escapement means, advance same across said front and rear runs of said tracks, and discharge same into said track end runs.

60. In a machine of the class described, in combination, a frame structure embodying two endless tracks arranged in spaced parallel relation, each said track including parallel front and rear runs connected by substantially semi-circular end runs; carriages extending between, supported by and adapted to be moved about said tracks; trunnions on the ends of said carriages protruding into the said tracks; sprockets journaled in pairs on said frame structure in spaced relation intermediate said track end runs; a conveyor chain trained over each said pair of sprockets; escapement means on said frame structure intermediate said sprockets and said track end runs, coacting with said carriage trunnion to retain said carriage between said escapement means about said track end runs when not in transit across said front and rear track runs; and actuator blocks on said conveyor chains coacting with said escapement means and carriage trunnions to successively engage and release said carriages from said escapement means, advance same across said front and rear track runs and discharge same into said track end runs, effecting successive and simultaneous transit of carriage across said front and rear track runs in intermittent timed relation.

61. In a machine of the character described, in combination, a frame structure embodying two endless tracks arranged in

- spaced parallel relation, each said track including parallel front and rear runs and substantially semi-circular end runs connected to said front and rear runs; carriages extending between said tracks; rollers on the ends of said carriages supported by said tracks adapted to keep said carriages in alignment with said front and rear track runs; escapement means for retaining said carriages about said end runs of said tracks when not in transit across said front and rear runs of said tracks; actuating means for said carriages supported by said frame structure coacting with said escapement means to successively release said carriages from said track end runs, advance same across said front and rear track runs, and discharge same into said track end runs in intermittent timed relation.
62. In a machine of the class described, in combination, a frame structure embodying two endless tracks arranged in parallel spaced relation, each said track including parallel front and rear runs and substantially semi-circular end runs connected to said front and rear track runs; carriages extending between said tracks; a plurality of rollers on each end of each said carriage running in said tracks to keep said carriages in alignment with said front and rear track runs; rollers on said carriages, the axes of which are substantially at right angles to the axes of the rollers aforesaid, adapted to bear against said frame structure, to prevent excessive longitudinal shifting of said carriages intermediate said tracks; escapement means for retaining said carriages about said end runs of said tracks; when not in transit across said front and rear runs of said tracks; actuating means for said carriages supported by said frame structure coacting with said escapement means to successively release said carriages from said track end runs, advance same across said front and rear track runs, and discharge same into said track end runs in intermittent timed relation.
63. In a machine of the class described, in combination, a frame structure embodying two endless tracks arranged in spaced parallel relation, each track embodying parallel front and rear runs connected by substantially semi-circular end runs; carriages extending between and supported by said tracks; a trunnion on each end of each said carriages protruding into said tracks; conveyor chains running parallel with said front and rear tracks runs intermediate said track end runs, whereby said end runs form accumulating magazines for said carriages; and actuator blocks on said conveyor chains each having spaced apart shoulders forming a recess for receiving said carriage trunnions, one said shoulder on each said actuator block being movable and normally out of the path of said carriage trunnions, and means substantially at the entrances of the front and rear track runs to shift said movable shoulders on said actuator blocks into the path of said carriage trunnions to couple the same to said actuator blocks.
64. In a machine of the class described, in combination, a frame structure embodying two endless tracks arranged in spaced parallel relation, each track embodying parallel front and rear runs connected by substantially semi-circular end runs; a carriage extending between and supported by said tracks; conveyor chains running parallel with said front and rear track runs intermediate said track end runs, whereby said end runs form accumulating magazines for said carriages; actuator blocks on said conveyor chains each having spaced apart shoulders forming a recess for receiving said carriage trunnions, one said shoulder on each said actuator block being movable and normally out of the path of said carriage trunnions, and means substantially at the entrances of the front and rear track runs to shift said movable shoulders on said actuator blocks into the path of said carriage trunnions to couple the same to said actuator blocks.
65. In a machine of the class described, in combination, a frame structure embodying two endless tracks arranged in parallel spaced relation, each track embodying parallel front and rear runs connected by substantially semi-circular end runs; a carriage extending between and supported by said tracks; a trunnion on each end of each said carriages protruding into said tracks; conveyor chains running parallel with said front and rear track runs intermediate said track end runs, whereby said end runs form accumulating magazines for said carriages; actuator blocks on said conveyor chains each having spaced apart shoulders forming a recess for receiving said carriage trunnions, one said shoulder on each said actuator block being movable and normally out of the path of said carriage trunnions; means substantially at the entrances of the front and rear track runs to shift said movable shoulders on said actuator blocks into the path of said carriage trunnions to couple the same to said actuator blocks; escapement means on said frame structure arranged in the path of said carriage trunnions and coacting therewith to hold said carriages at the entrances to said front and rear track runs; and means on said actuator blocks coacting with said stationary means to release said escapement means out of the path of the travel of said carriage.

trunnions simultaneously with the coupling action of said actuator block shoulders with said carriage trunnions.

66. In a machine of the class described, in combination, a frame structure embodying a track run including a carriage magazine at one end of said track run; carriages movable from said magazine along said track run; means for actuating said carriages including a conveyor having a portion extending adjacent to said track run and spaced apart from said magazines; an actuator block carried by said conveyor; a supporting track for said actuator block terminating at the exit end of said magazine in a form of a cam; and a coupling carried by said actuator block for picking up said carriages at the exit of said magazine; said coupling being normally held out of coupling position and coacting with said cam to shift said coupling into coupling position.

67. In a machine of the class described, in combination, a frame structure embodying a track run including a carriage retaining magazine at one end of the track run, carriages movable in said magazine and therefrom along the track run, escapement means at the end of the magazine to hold the carriages in said magazine, a pair of curtain rolls mounted on each carriage, curtains connecting the rolls of said pairs in series, means to effect the rolling of the curtain from the first roll of a pair of rolls moving along the track run and rolling up the curtains previously unrolled on the second roller of the pair of rolls moving along the track run out of the magazine, a conveyor for said carriages terminating adjacent said magazine, and escapement means at the end of the magazine to hold the carriages in said magazine, said carrier having means to actuate the escapement means and withdraw the carriages one by one from the magazine.

In testimony whereof, I have hereunto signed my name, at Syracuse, in the county of Onondaga, and in the State of New York, this 19th day of October, 1928.

HENRY ARMSTRONG.
